ATTORNEY

UNITED STATES PATENT OFFICE.

JAMES A. FULLER, OF PROVIDENCE, RHODE ISLAND, ASSIGNOR TO
HAMILTON & HAMILTON, JR., OF PROVIDENCE, RHODE ISLAND,
A FIRM.

BRACELET.

No. 825,644.

Specification of Letters Patent.

Patented July 10, 1906.

Application filed October 30, 1905. Serial No. 285,079.

To all whom it may concern:

Be it known that I, JAMES A. FULLER, a citizen of the United States, residing at Providence, in the county of Providence and State 5 of Rhode Island, have invented a new and useful Improvement in Bracelets, of which the following is a specification.

This invention has reference to an improvement in bracelets, and more particularly to an improvement in concealed spring 10 snaps or catches for bracelets.

Hinged bracelets as heretofore constructed are usually formed of two equal halves or members hinged together and secured in the 15 closed position by a snap or catch. In the use of bracelets I find that it is only necessary to open approximately one-quarter of the bracelet to clasp the bracelet on the arm or wrist of the wearer; also, a bracelet thus 20 constructed has a more desirable appearance and when worn with the hinged portion on the under side of the arm or wrist has the appearance of an endless or one-piece bracelet.

The object of my invention is to improve 25 the construction of a hinge-bracelet whereby the hinged portion is approximately one-quarter the size of the bracelet and held in the closed position by a spring-snap, the action of which is automatic and the construction more durable than has heretofore 30 been attained.

My invention consists in the peculiar and novel construction of a hinged bracelet, the hinged portion of which is approximately 35 one-quarter the circumference of the bracelet, and a spring-snap adapted to catch automatically and hold the hinged portion in the closed position with details of construction, as will be more fully set forth hereinafter.

Figure 1 is a side view of my improved hinged bracelet, showing the bracelet in the closed position in full lines and in the open position in broken lines. Fig. 2 is an enlarged detail sectional view of the snap portion 40 of the bracelet, taken on line X X of Fig. 1, showing the snap in the position it would assume with the bracelet in the closed position. Fig. 3 is an enlarged detail sectional view taken on line Y Y of Fig. 2 with 45 the bracelet and snap in the closed position. Fig. 4 is an enlarged detail sectional view similar to Fig. 3, showing the bracelet and snap in an open position; and Fig. 5 is an

enlarged perspective view of the two members of the snap removed from the bracelet 55 and shown in a separated position. Fig. 6 is a sectional view taken through line 6 6 of Fig. 5.

In the drawings, *a* indicates the body portion, *b* the hinged portion, *c* the hinge, and *d* 60 the catch, of my improved bracelet.

The body portion *a* and the hinged portion *b* are constructed from a tube which is oval in cross-section and bent to form the contour of the bracelet, which is preferably oval, 65 as shown in Fig. 1. The body portion *a* has an opening in the under side approximately one-quarter the circumference of the bracelet, forming the end *a*² for the hinge *c* and the beveled end *a*² for the snap *d*. The hinged 70 portion *b* has the end *b*² for the hinge *c* and the beveled end *b*² for the snap *d*. The ends *a*² and *b*² coincide when the bracelet is closed. The hinge *c* may have the construction of any 75 of the well-known forms of hinges adapted for bracelets.

The snap *d* consists of the rigid member *d*² and the spring member *d*². The rigid member *d*² is stamped from sheet metal in an elongated form with the oppositely-disposed 80 side notches *d*³ *d*³ forming the neck *d*⁴ and then bent **U** shape, thus bringing the notches *d*³ *d*³ in the outer face of the member and the neck *d*⁴ adjacent the bend, as shown in Fig. 5. The member *d*² is secured in the end *a*² of the 85 bracelet in a position, as shown in Figs. 2 and 4, by solder. The spring member *d*² is formed of spring-wire approximately square in cross-section and bent **U** shape to form the closed end *d*⁵, the spring side arms *d*⁶ *d*⁶, the ends of 90 which are bent toward each other, to form the **L**-shaped ends *d*⁷ *d*⁷, as shown in Fig. 5. The space between the **L**-shaped ends *d*⁷ *d*⁷ is slightly less than the width of the neck *d*⁴ on the fixed member *d*². The spring member *d*² 95 is secured adjacent the end *d*⁵ in the end *b*² of the hinged member *b* in a position, as shown in Figs. 2 and 4, by solder.

In the operation of my improved bracelet the bracelet is closed by an inward pressure 100 on the end *b*² of the hinged portion *b* and held in the closed position by the **L**-shaped ends *d*⁷ *d*⁷ on the member *d*² being sprung apart by the neck *d*⁴ passing through the notches *d*³ *d*³ and snapping under the neck 105 *d*⁴, as shown in broken lines in Fig. 2. The

bracelet is also held from expanding by the L-shaped ends d^7 d^7 engaging with the inner face of the bent end of the rigid member d' , as shown in Figs. 2 and 3. The hinged portion b of the bracelet may be opened, as shown in broken lines in Fig. 1, by a strong outward pull on the end b^2 , thus forcing the ends d^7 d^7 outward over the neck d^4 , which may be slightly rounded, and releasing the members of the snap.

Having thus described my invention, I claim as new and desire to secure by Letters Patent—

1. A two-part hinged bracelet having means for pivotally securing the parts together, and means for holding the parts in the closed position consisting of a snap comprising a rigid member formed from a strip of sheet metal, bent U shape and constructed to have oppositely-disposed side notches and a neck on the face of the member adjacent the bent end of the same, and a spring member formed of spring-wire bent U shape forming spring-arms with inwardly-bent L-shaped ends, and means for securing the members of the snap in the bracelet, as described.
2. A bracelet comprising a body portion and a hinged portion, means for pivotally securing the hinged portion to the body portion, means for holding the hinged portion in the closed position consisting of a snap comprising a U-shaped rigid member having two oppositely-disposed side notches and a neck adjacent the bent end of the member and a spring member constructed of spring-wire bent U shape and having spring side arms with inwardly-bent L-shaped ends, and means for securing the members of the snap

in the body and hinged portions of the bracelet 40 let, as described.

3. A snap for bracelets comprising a rigid member d' constructed from sheet metal bent U shape and having the two oppositely-disposed side notches d^3 d^3 and the neck d^4 45 adjacent the bent end, and a spring member d^2 constructed of spring-wire bent U shape and having the closed end d^5 , the spring side arms d^6 d^6 with the inwardly-bent L-shaped ends d^7 d^7 , and means for securing the members of the snap in position, as described.

4. In combination, a bracelet having the body portion a with the hinge end a^1 and the beveled end a^2 , a hinged portion b having the hinge end b^1 and the beveled end b^2 , a hinge c pivotally securing the hinged portion b to the body portion a , a snap d adapted to hold the hinged portion b in the closed position and comprising a rigid member d' constructed from sheet metal bent U shape and 60 having the two oppositely-disposed side notches d^3 d^3 and the neck d^4 all formed integral, and a spring member d^2 constructed of spring-wire bent U shape and having the closed end d^5 , the spring side arms d^6 d^6 with 65 the inwardly-bent L-shaped ends d^7 d^7 all formed integral, and means for securing the member d' in the end a^2 of the bracelet and the member d^2 in the end b^2 of the hinged portion b in position, as described.

In testimony whereof I have signed my name to this specification in the presence of two subscribing witnesses.

JAMES A. FULLER.
